UNITED STATES PATENT OFFICE.

WILLIAM DAVID THURMOND, OF FORSYTH, GEORGIA, ASSIGNOR TO THE THURMOND CAR COUPLING COMPANY, OF WEST VIRGINIA.

CAR-CO尤LING.

SPECIFICATION forming part of Letters Patent No. 430,709, dated June 24, 1890.

Application filed February 27, 1890. Serial No. 341,964. (No model.)

To all whom it may concern:

Be it known that I, WILLIAM DAVID THURMOND, a citizen of the United States, residing at Forsyth, in the county of Monroe and 5 State of Georgia, have invented certain new and useful Improvements in Car-Couplings; and I do hereby declare the following to be a full, clear, and exact description of the invention, such as will enable others skilled in the 10 art to which it appertains to make and use the same.

My present invention relates to certain improvements upon that class of car-couplings known as "twin-jaw" couplings, to which 15 class applications filed by me May 5, 1888, Serial No. 272,896, and September 13, 1889, Serial No. 323,855, belong, and I do not therefore desire to claim anything herein which is claimed in either of the said applications; but 20 this invention differs from those hereinbefore mentioned in the device used for relieving the pivot-pin from strain, and also in having an improved locking-bolt, whereby the pivoted hook or knuckle is locked against rotation, as will be hereinafter more fully 25 described and claimed.

Referring to the accompanying drawings, in which corresponding parts are designated by similar letters, Figure 1 is a horizontal longitudinal section of a coupling constructed 30 according to this invention, taken on the line $x' x'$ of, Fig. 2, showing the hook locked and in the position which it occupies when coupled with a corresponding coupler upon a straight 35 or medium curved track, its position when opened for coupling or after uncoupling being shown in dotted lines. Fig. 2 is a vertical central longitudinal section on line $x x$ of Fig. 1, the locking-bolt having a pivoted 40 link attached to its top for lifting it. Fig. 3 is a vertical cross-section on the lines $x^2 x^2$ of Figs. 1 and 2, the shank of the knuckle being shown fully home within the draw-head and locked in that position. Fig. 4 is a vertical cross-section on the same lines as Fig. 3, 45 the locking-bolt having a cap provided with an eye on its top in the place of the link shown in Figs. 2 and 3, the shank of the knuckle being locked in the position which it occupies after coupling on a sharp curve.

Fig. 5 is a vertical cross-section on the same lines as Figs. 3 and 4 and upon the line $x^3 x^3$ of Fig. 6, having another form of tipping mechanism for the locking-bolt connected therewith, and having the lock-bolt held up 55 by the shank of the knuckle, the parts having the position which they occupy when in the act of uncoupling. Fig. 6 is a central vertical longitudinal section on line $x^4 x^4$ of Fig. 5. Fig. 7 is a rear view of the locking-bolt shown in 60 Figs. 5 and 6. Fig. 8 is a rear and front view of the latch shown in Figs. 5 and 6. Fig. 9 is a side view of the locking-bolt shown in Fig. 4, taken from the side adjoining the chamber a^2 . Fig. 10 is a horizontal section of the locking-pin on the line $x^5 x^5$ of Figs. 4 and 9. Fig. 11 is a perspective view of the coupling-hook. Fig. 12 is a front view of the locking-pin.

The coupler is constructed of three principal parts, the draw-bar A, the pivoted hook 70 B, and the locking-bolt C, the two former of which are the same for all forms of my invention shown herein, and will be therefore first described.

The jaw A' of the draw-head is provided 75 with ears a' , between which the hook B is pivoted, and is chambered at a^2 sufficiently to allow the hook B to swing in and out. The face of a projecting part a^3 of the vertical wall of the chamber a^2 , as well as the rear 80 face b of the hook-shank, lie in segments of circles whose common center is the axis of rotation of the hook B, there being just sufficient space between the end of the hook and the projecting part a^3 of the vertical wall of 85 the chamber to admit of the hook-shank moving in and out freely. The ears a' , in which the hook is pivoted, and the opposite horizontal faces forming the roof and bottom of the chamber a^2 in the jaw are reduced in thickness, so as to leave curved shoulders a^4 and 90 a^5 , the faces of which also lie in arcs of circles whose centers are in the axis of rotation of the hook.

The shank of the hook B has upon its upper and lower faces near its pivotal point a shoulder b' , and near its rear end a shoulder b^2 , the former bearing against the shoulder a^4 and the latter against the shoulder a^5 of the draw-head, the hook being thus held against 95

endwise movement, whatever may be its position, so long as a portion of the same within remains within the draw-head. The amplitude of the rotary motion of the hook is limited outwardly by the shoulder a^6 on the draw-head, so that the hook-shank can at no time swing fully out of the draw-head so long as the pivot pin or bolt P remains in position.

10 In the hereinbefore-mentioned applications I have shown corresponding grooves upon the roof and floor of the chamber a^2 and corresponding tongues upon the upper and lower faces of the shank of the knuckle; but in my present invention I substitute therefor a lug A^2 upon the inner surface of the outer wall of the chamber a^2 , which engages with a corresponding recess b^3 in the outer surface of the shank of the hook when the latter is sufficiently within the draw-head to be locked by the locking-bolt. The faces of the lug and recess are struck by arcs of circles whose centers are in the axis of rotation of the hook B. As no pulling strain is upon the coupler 25 until the hook is locked against opening and no buffing strain until the shank has fully entered the chamber, it will be seen that at these times the lug A^2 will have entered the recess in the hook. The hook is guided in 30 its movement in coupling and uncoupling by the shoulders a^4 and a^5 , and as the lug A^2 and shoulders a^4 and a^5 and projecting part a^3 of the vertical wall of the chamber a^2 form abutments or bearings which take up all the 35 force of the end-thrust on the hook, it will be readily seen that all strain or shearing action upon the pivot-pin of the hook is avoided, and that a plurality of pivotal bearings a are provided for the hook, so that should the pivot- 40 pin P break, or be accidentally or designedly removed, the hook could not be drawn out of the draw-head so long as the recess b^3 therein is in engagement with the lug A^2 on the draw-head. As the inner end of the hook-shank 45 fits snugly against the projection a^3 of the draw-head, snow, ice, or dirt that may have accumulated on the hook when drawn out, is sheared or scraped off when the hook-shank is pushed into the chamber of the jaw. It 50 will also be seen that the rear shoulders b^2 on the hook-shank form a tail-piece b^4 thereon of less thickness than the main portion of the shank.

The locking-bolt C is fitted in such a manner as to be capable of a vertical upward and 55 downward movement within an upright chamber a^7 , which intersects the line of draft or longitudinal axis of the coupler, and also the chamber a^2 of the draw-head. The locking-bolt C has a recess c' of curvilinear form, its line of curvature being a segment of a circle in which the coupling-hooks swing, so that when the locking-bar is lifted in uncoupling 60 the tail-piece of the hook can swing outward through the recess, and the locking-bar can rest thereon. In other words, when the hook swings out a portion of the tail-piece b^4 on

the shank thereof will remain within the draw-head, and the shoulder c^2 above the curvilinear recess c' of the bolt will rest upon 70 the tail-piece of the shank.

The body of the locking-bolt C, which is rectangular when the coupling-hook is locked, lies in front of the tail thereof, and in order to permit the hook being locked on curves 75 has a portion c^3 of its side which is adjacent to and faces the tail-piece b^4 of the shank of the hook, and which is immediately above the recess c' , slightly cut away, forming a step, while the forward end of the tail-piece 80 b^4 has its upper portion also cut away, forming a corresponding step b^5 , as shown; but it is evident that a step upon either one of the said parts may be used without a step upon the other, or that both may be used together. 85 From an examination of Figs. 3, 4, and 5 it will be seen that when the shank is fully within the chamber a^2 , Fig. 3, the rise of the step c^3 of the bolt bears against the forward face of the base of the tail-piece, while the 90 side of the locking-bolt will bear upon the rise of the step b^5 , and that if the shank of the hook is partly out of the chamber the rise of the step c^3 on the bolt will engage the rise of the step b^5 on the tail-piece, thus giving 95 two points at which the hook may be locked against rotation, and permitting my invention to be coupled on curves on which the shank is not forced fully home. It will also be seen that the locking-bolt cannot be 100 entirely lifted from the chamber a^7 , while the hook is in place, as the shoulder c^9 below the curvilinear recess c' will strike the bottom of the forward end of the tail-piece; and in this connection it may be stated that 105 to accomplish this result and limit the upward movement of the locking-bolt it is only necessary that a portion of the shank of the hook when forced fully home project past and above a portion of the locking side of its 110 base, which will strike the lower surface of the shank of the hook, and it will be noticed that in the construction adopted by me the said shoulder is flush with the forward and locking sides of the bolt. I also strengthen 115 the locking-bolt by carrying the rear and side walls a^8 of the chamber a^7 , in which it is contained from the top to the bottom of the draw-head, giving it an extensive bearing for assistance in resisting the shocks and strains 120 to which the bolt is subjected.

If desired, the locking-bolt may be lifted and set for uncoupling, staying in this position any desired length of time without requiring it to be held up by the brakeman. 125 To do this I form a notch or shoulder c^4 on the forward face of the locking-pin near its bottom, which, when lifted, may be caught by the floor of the recess in the jaw A' . To do this it is necessary that the lower end of 130 the locking-bolt be thrown forward, and I have shown several forms of devices for this purpose.

The link e, attached to the top of the lock-

ing-bolt in Fig. 2, or the eye e' on the top thereof, (shown in Fig. 9,) may be located forward of the vertical plane of the center of gravity of the bolt, causing it when lifted to swing to the desired inclination; or the means for lifting the bolt may be connected thereto from the rear, as shown in the chain e^2 in Fig. 9, or the automatic tipping mechanism shown in Figs. 5, 6, 7, and 8, which I will now describe, may be used.

A vertical longitudinal slot c^5 is cut in the central portion of the locking-bolt, the said slot having near its bottom recesses c^6 upon each side thereof, that portion of the slot 15 above the recess opening at the rear upon the rear surface of the bolt C, while below the recesses the slot is covered. A lifting-plate D of substantially triangular form, having its apex within the covered portion of the slot, 20 has shoulders d^2 , which fit within the recesses c^6 , while the plate D passes up through the slot c^5 and through the cover a^9 of the chamber. The shoulders d^2 have beveled forward upper edges, and may also have beveled rear 25 lower edges, which engage with the corresponding beveled edges of the recesses c^6 . It is obvious from an examination of this construction that when the lifting-plate D is raised the locking-bolt will move with it, and that 30 the beveled upper edges upon the lifting-rod working against the inclined edges upon the locking-bolt will force the latter forward, so that the shoulder c^4 will rest upon the bottom of the chamber a^2 . The locking-bolt being 35 thus set for uncoupling, when the hook swings outward the shank thereof comes into contact with it and moves it backward, thus forcing the shoulder c^4 from its resting place on the floor of the chamber, and causing the bolt to 40 drop until the upper shoulder c^2 rests upon the upper surface of the tail-piece of the shank.

In order to render it more certain that the locking-pin will be forced backward when 45 the tail-piece of the shank leaves the chamber a^2 , I may place on the forward end of the tail-piece a beveled face b^6 , which will strike the curvilinear recess c' of the bolt and force it backward; or a second curvilinear face c^7 , 50 as shown in Fig. 10, may be cut in the locking-bolt on the locking side thereof on a plane with curvilinear face c' , against which the rear end of the shank tail-piece will strike, forcing it backward; or the beveled face b^6 on 55 the tail-piece and the curvilinear face c^7 may be used simultaneously and together.

It may be sometimes desired to drop the locking-bolt after it has been raised and without pulling out the coupling-hook, and 60 this result may be obtained by pushing backward the forward upper face d^3 of the lifting plate or latch D, as by so doing the bottom of the plate will be thrown backward, and its end being engaged in the lower part of the 65 slot will throw the locking-bolt backward; or if the shoulders d^2 have rear lower beveled edges, as shown, they will engage the corre-

sponding faces in the recesses and cause the same result.

The locking-bolt can be inserted in its 70 chamber either from the top or bottom, in the form shown in Fig. 4, it being inserted from the top, while in Figs. 2, 3, 5, and 6, it is shown inserted from the bottom.

In the form shown in Fig. 4 a head e^4 is 75 formed upon the top of the locking-bolt and rests upon the top of the draw-head when the bolt is fully down, and is protected when raised by the walls e^5 , formed on the top of the draw-head.

In the form shown in Figs. 2, 3, 5, and 6 the chamber a^7 has a cap formed integral therewith, as a^9 , through which the link e or plate D extends, and in Fig. 2 I have shown a plate e^6 projecting into the chamber a^5 to 85 afford a rest for the shoulder c of the locking-bolt. In the figures last named the bolt is prevented from falling out while the knuckle is in place by the tread of the step c^8 therein resting upon either the top of the tail-piece 90 of the hook or upon the tread of the step b^5 formed therein, or by the shoulder c^2 resting upon the top of the tail-piece.

Having thus described my invention, what I claim, and desire to secure by Letters Patent, is—

1. In a car-coupling, the combination, with a draw-head, of a pivoted hook, a coupling-bolt having a vertical movement in the said draw-head in the path of the shank of the said hook, the said bolt having a curvilinear recess in its forward face, and having a step in its side contiguous to the said shank, as described.

2. In a car-coupling, the combination, with a draw-head, of a pivoted hook, a locking-bolt having a vertical movement in the said draw-head in the path of the shank of the said hook, a curvilinear recess on the forward face of the locking-bolt, a shoulder beneath the said recess, recesses having forward upper beveled faces in the rear of the said locking-bolt, and a latch having its lower end engaged by a covered slot in the rear of the locking-bolt, and having shoulders with forward upper beveled faces upon its sides, the said shoulder being received by the rear recesses in the locking-bolt, as described.

3. In a car-coupling, the combination, with a draw-head, of a pivoted hook, a locking-bolt having a vertical movement in the said draw-head in the path of the shank of the said hook, a curvilinear recess on the forward face of the locking-bolt, and a shoulder beneath the said recess, recesses having upper forward and lower rear beveled faces on the back of the said locking-bolt, and a latch having shoulders upon its sides received by the said recesses in the rear of the locking-bolt, the said shoulders having upper forward and rear lower beveled faces, as described.

4. In a car-coupling, the combination, with a draw-head, of a pivoted hook, a coupling-bolt having a vertical movement in the said draw-

- head in the path of the shank of the said hook, a curvilinear recess on the forward face of the locking-bolt, and a shoulder beneath the said recesses, recesses having upper forward and lower rear beveled faces in the back of the said locking-bolt, and a latch having its lower end engaged in a covered slot in the rear of the locking-bolt, and having shoulders upon its sides received by the said recesses in the rear of the locking-bolt, the said shoulders having upper forward and rear lower beveled faces, as described.
5. In a car-coupling, the combination, with a draw-head having a hook pivotally attached thereto, of a vertically and laterally moving locking-bolt mounted in the said draw-head in the path of the shank of the said hook, the said locking-bolt having a recess in its forward face for the passage of the said shank, 15 and a curved face on its side contiguous to the said shank and on a level with the recess in its forward face, whereby the bolt will be forced backward upon a rotation of the hook, as described.
10. In a car-coupling, the combination, with a draw-head having a hook pivotally attached thereto, of a vertically and laterally moving locking-bolt mounted in the said draw-head in the path of the shank of the said hook, the 20 said locking-bolt having a recess in its forward face for the passage of the said shank, and a curved face on its side contiguous to the said shank and on a level with the recess in its forward face, whereby the bolt will be forced backward upon a rotation of the hook, as described.
15. In a car-coupling, the combination, with a draw-head having a hook pivotally attached thereto, of a vertically and laterally moving locking-bolt mounted in the said draw-head in the path of the shank of the said hook, the 25 said shank having a tail-piece thereon, having a forward beveled edge, and the said locking-bolt having a curvilinear recess in its forward face for the passage of the said tail-piece, and a curved face on its side contiguous to the said tail-piece and on a level with the recess in its forward face, whereby the bolt will be forced backward, as described.
20. In a car-coupling, the combination, with a draw-head, of a pivoted hook having a step upon the upper part of the rear end of its shank and a locking-bolt having a vertical movement in the said draw-bar and in the path of the said shank, as described.
25. In a car-coupling, the combination, with a draw-head, of a pivoted hook and a locking-bolt having a vertical movement in the said draw-head in the path of the shank of the said hook, the said hook having a step upon the upper part of its shank, and the said locking-bolt having a step in its side contiguous to the said shank, as described.
30. In a car-coupling, the combination, with a draw-head, of a hook pivoted therein, and having a tail-piece upon its shank, and a vertically-moving locking-bolt having a recess in its forward face for the passage of the said tail-piece and a step in its side contiguous to the said tail-piece and to the said recess in its face, as described.

35. In a car-coupling, the combination, with a draw-head, of a hook pivoted therein, and having a tail-piece upon its shank, and a vertically-moving locking-bolt having a recess in its forward face for the passage of the said tail-piece and a step in its side contiguous to the said tail-piece and to the said recess in its face, as described.

40. In a car-coupling, the combination, with a draw-head, of a hook pivoted therein, and having a tail-piece upon its shank, and a vertically and laterally moving locking-bolt mounted in the said draw-head in the path of the tail-piece, the said locking-bolt having a recess in its forward face for the passage of the said tail-piece and a step in its side contiguous to the said tail-piece and to the said recess in its face, as described.

45. In a car-coupling, the combination, with a draw-head, of a hook pivoted therein, and having a tail-piece upon its shank, and a vertically-moving locking-bolt having a recess in its forward face for the passage of the said tail-piece and a step in its side contiguous to the said tail-piece and to the said recess in its face, and a shoulder in the said bolt, whereby it may be retained in a raised position.

50. In a car-coupling, the combination, with a draw-head, of a hook pivoted therein, and having a tail-piece upon its shank, and a vertically-movable locking-bolt mounted in the said draw-head, having a recess in its forward and in its locking side, a shoulder on the said bolt below the said recesses, the said shoulder being flush with the forward and locking sides of the bolt, a portion of the shank of the hook being constantly within one of the said recesses, whereby the upward movement of the locking-bolt will be limited, as described.

55. In a car-coupling, the combination of pivoted hook having a recess in the rear of its shank, a draw-head in which the said hook is mounted, having a lug thereon projecting into the said recess, and a vertically-moving locking-bolt arranged in the path of the said shank, and having a recess therein for the passage of the said shank, and a supporting-shoulder upon its face, as described.

60. In testimony whereof I have affixed my signature in presence of two witnesses.

WILLIAM DAVID THURMOND.
